UNITED STATES PATENT OFFICE.

JAMES A. SKINNER, OF EAST ORANGE, AND HAROLD D. THOMAS, OF BLOOMFIELD, NEW JERSEY.

VALVE MECHANISM.

1,134,493.

Specification of Letters Patent.

Patented Apr. 6, 1915.

Application filed June 25, 1914. Serial No. 847,352.

To all whom it may concern:

Be it known that we, JAMES A. SKINNER and HAROLD D. THOMAS, citizens of the United States, residing at East Orange, in the county of Essex and State of New Jersey, and at Bloomfield, county of Essex, and State of New Jersey, have invented certain new and useful Improvements in Valve Mechanism; and we do hereby declare the following to be a full, clear, and exact description of the invention, such as will enable others skilled in the art to which it appertains to make and use the same, reference being had to the accompanying drawings, and to characters of reference marked thereon, which form a part of this specification.

The present invention relates, generally, to improvements in shut-off valve mechanism; and the invention has reference, more particularly, to a novel valve mechanism for controlling the flow of a plurality of fluids or gases through supply pipes or conduits.

The present invention has for its principal object to provide a novel and simple construction of valve mechanism adapted for use in blow pipes or torches for turning on and off the supply of air and gas passing through the supply pipes to the burner or torch, together with a novel valve operating mechanism whereby the opening and closing of the valve is easily and quickly accomplished.

Another object of the present invention is to provide in connection with said valve mechanism by-pass ports through which, when the valve mechanism is shut off or closed, a very small volume of gas is permitted to pass therethrough for the purpose of supplying a pilot or ignition flame at the burner or torch when not in use, so that the same will be immediately and automatically ignited when the valve mechanism is turned on or opened.

Another object of the present invention is to provide in connection with said valve mechanism an adjustment means whereby the by-pass ports may be adjusted therethrough to the pilot or ignition flame of the burner or torch.

Still another object of the present invention is to provide a novel means for mounting and supporting said valve mechanism so that the same may be readily attached to a

work-bench or other place at which the blow- 55 pipe or torch is desired to be used.

Other objects of the present invention, not at this time more particularly enumerated, will be clearly understood from the following detailed description of the said invention.

With the various objects of the present invention in view, the said invention consists, primarily, in the novel valve mechanism hereinafter more fully set forth, and the 65 said invention consists, furthermore, in the novel arrangements and combinations of the various devices and parts, as well as in the details of the construction of the same, all of which will be hereinafter more fully described, and then finally embodied in the 70 claims which are appended to this specification, and which form an essential part thereof.

The invention is clearly illustrated in the 75 accompanying drawings, in which:—

Figure 1 is a side elevation of the novel valve mechanism made according to and embodying the principles of the present invention, the mechanism being illustrated therein 80 operated to its opened or turned on position; Fig. 2 is a similar side elevation of the novel valve mechanism operated to its closed or shut off position. Fig. 3 is an elevation of the opposite side of said novel valve 85 mechanism. Fig. 4 is a detail horizontal cross section taken on line 4—4 in said Fig. 1, looking in the direction of the arrow *x*, said view being drawn on an enlarged scale. Fig. 5 is a detail vertical cross section taken 90 on line 5—5 in Fig. 3 looking in the direction of the arrow *y*, said view being also drawn on an enlarged scale. Fig. 6 is a detail transverse section taken on line 6—6 in said Fig. 4, looking in the direction of the 95 arrow *z*; and Fig. 7 is a detail horizontal cross section taken on line 7—7 in said Fig. 6 looking downward. Fig. 8 is a similar transverse section to that shown in Fig. 6, but illustrating the valve mechanism in its 100 closed or shut off position; and Fig. 9 is a detail horizontal cross section taken on line 9—9 in Fig. 8 looking downward.

Similar characters of reference are employed in all of the hereinabove described 105 views to indicate corresponding parts.

Referring now to the said drawings, the reference character 1 indicates the complete

novel valve mechanism made according to and embodying the principles of our present invention, the same comprising a suitable frame-member 2, the base 3 of which is adapted to be supported upon the edge of a work-bench, table or other suitable location as indicated at 4, and extending downwardly from said frame-member 2 and integrally formed therewith is an arm or extension 5, 10 at the lower free end of which is a forwardly extending bracket-piece 6, the latter being provided with an interiorly screw-threaded opening in which is arranged a clamp-screw 7, which is adapted to be moved against the 15 under side of said work-bench or table 4 for the purpose of rigidly clamping said frame-member 2 to said work-bench or table. Said frame-member 2, thus formed, is provided with laterally extending marginal flanges 8 20 which serve to strengthen and reinforce said frame-member. Of course, it will clearly be understood that the shape and general design of said frame-member 2 may be variously modified when so desired, hence we do not limit ourselves to the exact construction 25 of frame-member herein described and illustrated in the accompanying drawings. Preferably said frame-member 2 is provided with a depressed portion 9, said depressed portion being provided with an opening 10.

Secured to the outer face 11 of said frame-member 2 is a stationary valve-plate 12, the same having suitably located perforated ears or lugs 13 through which pass fastening 30 screws 14 which screw into said frame-member 2 and serve to secure said stationary valve-plate 12 in proper fixed and supported relation to said frame-member. Said stationary valve-plate 12 is provided on its inner side with a hub or boss 15 which is inserted through said opening 10 of said depressed portion 9 of said frame-member. The surface of said hub or boss 15 is prepared to provide a ground or smooth bearing surface 16. The outer face of said stationary valve-plate 12 is provided with integrally formed and oppositely projecting socket-portions 17 and 18 the same being 40 each provided with their respective sockets 19 and 20, the former serving to secure an outwardly projecting tubular coupling-pipe 21 to which is attached an air supply hose 22 leading from the source of air supply, and the latter serving, in like manner, to secure 45 an outwardly projecting tubular coupling-pipe 23 to which is attached an air conveying hose 24 leading to the air jet of the burner or torch of a blow-pipe or similar apparatus. Formed in said stationary valve-plate 12 is an air intake port 25, the mouth of which terminates at the ground surface 16 of said hub or boss 15, and the inner end of which communicates with said socket 19. In 50 like manner, formed in said stationary valve-plate 12 is an air outlet port 26, the

mouth of which terminates at the ground surface 16 of said hub or boss 15, and the inner end of which communicates with said socket 20. The outer face of said stationary valve-plate 12 is further provided with suitably located integrally formed and oppositely projecting socket-portions 27 and 28 the same being each provided with their respective sockets 29 and 30, the former serving to secure an outwardly projecting tubular coupling pipe 31 to which is attached a gas supply hose 32 leading from the source of gas supply, and the latter serving, in like manner, to secure an outwardly projecting tubular coupling pipe 33 to which is attached a gas conveying hose 34 leading to the gas jet of the burner or torch of a blow-pipe or similar apparatus. Formed in said stationary valve-plate 12 is a gas intake port 35, the mouth of which terminates at the ground surface 16 of said hub or boss 15, and the inner end of which communicates with said socket 29. In like manner, formed in said stationary valve-plate 12 is a gas outlet port 36, the mouth of which terminates at the ground surface 16 of said hub or boss 15, and the inner end of which communicates with said socket 30. Communicating with the mouth of said gas intake port 35, and extending from the circumference thereof, 55 is a by-pass channel or groove 37 formed in said ground surface 16 of said hub or boss 15. The reference character 38 indicates a rotary valve-plate, the inner side of which is dressed or machined to provide a ground or smooth surface 39 adapted to be registered against said ground surface 16 of the boss or hub 15 of said stationary valve-plate 12 so as to slide thereupon. The reference character 40 indicates a screw or equivalent device connected with said stationary valve-plate 12, the same forming a journal upon which said rotary valve-plate 38 is rotatably mounted. Said rotary valve-plate 45 is provided with a suitably located connecting air channel or groove 41 formed in said ground surface 39, which, when said rotary valve-plate is in normal position registers with or straddles the mouths 50 of said air intake port 25, and air outlet port 26 of said stationary valve-plate 12, so as to permit the air to flow from the former into and through the latter, and thence to the air jet of the burner or torch 55 of the blow-pipe or similar device. In like manner, said rotary valve-plate is further provided with a suitably located connecting gas channel or groove 42 formed in said ground surface 39, which, when said rotary valve-plate 60 is in normal position registers with or straddles the mouths of said gas intake port 35 and gas outlet port 36 of said stationary valve-plate 12, so as to permit the gas to flow in full volume from the former 65

into and through the latter, and thence to the gas jet of the burner or torch of the blow-pipe or similar device. When said rotary valve-plate 38 is rotated said connecting gas channel or groove 42 and said connecting air channel or groove 41 are oscillated out of registration with the respective gas ports and air ports of said stationary valve-plate 12, therefore preventing the flow 10 of the full volume of gas from the gas intake port to and through the gas outlet port, and the flow of air from the air intake port to and through the air outlet port. In order to provide, however, for the flow of a minimum 15 volume of gas, even when the rotary valve-plate 38 is moved to shut-off position, the ground surface of the same is provided with a suitably located by-pass channel or groove 43 extending circumferentially from one end 20 of said connecting gas channel or groove 42, which, when said rotary valve-plate is oscillated to shut-off position, registers with said by-pass channel or groove 37 formed in said stationary valve-plate 12 and leading from 25 said gas intake port 35, so that a small volume of gas is permitted to flow from said gas intake port 35 through said registered by-pass channels or grooves 37 and 43 into said connecting gas channel or groove 42 30 and thence through said gas outlet port 36, so that a small quantity of gas flows continuously to supply a pilot light at the gas jet of the burner or torch of the blow-pipe or similar apparatus.

In Figs. 6 and 7 the rotary valve-plate 38 is illustrated in its open or turned on position, while in Figs. 8 and 9 the rotary valve-plate 38 is illustrated in its shut-off position, and the operative arrangement and 40 position of said respective by-pass channels or grooves 37 and 43 is illustrated so as to be clearly understood from an inspection of said figures of the drawings.

The means for operating said rotary valve-plate 38 comprises a lever-arm 44 which is pivoted upon a journal-stud 45 suitably located and connected with said frame-member 2. Said lever-arm 44 is provided with an extension portion 46 having 50 a downwardly and inwardly inclined portion 47, projecting inwardly from which is a pin or lug 48. Said rotary valve-plate 38 is provided with an outwardly or radially extending arm or projecting portion 49, which is provided in its periphery with a receiving slot 50 adapted to receive said pin or lug 48 whereby the movement of said lever-arm 44 and the ports connected therewith is transmitted to said rotary valve-plate 38. Said flange 8 of said frame-member 2 is provided with a stop-boss 51 against which the free end of said extension portion 46 is stopped to limit the upward movement 55 of said lever-arm 44. Connected between 60 said lever-arm 44 and said flange 8 of said

frame-member 2 is a pull-spring 52 which serves to maintain and retain said lever-arm 44 in normal position as stopped by said stop-boss 51. When said lever-arm 44 is in its normal position, as above described, it 70 serves to move or rotate said rotary valve-plate to its open or turned on position, so that its respective connecting channels or grooves register with the respective air and gas ports of the stationary valve-plate 12, 75 thereby permitting the flow of a full volume of both air and gas to the blowpipe burner or torch. When said lever-arm 44 is pressed or swung downward it serves to rotate said rotary valve-plate 38 to its closed or shut 80 off position, so that its respective connecting channels or grooves are carried out of registration with the respective air and gas ports of the stationary valve-plate 12, thereby shutting off the flow of air, and shutting 85 off the flow of gas except such as is permitted to pass through the by-pass grooves or channels for the purpose of supplying fuel to the pilot light or flame of the blowpipe burner or torch. The reference character 53 indicates a suitably located adjustable stop-screw which is connected with the flange 8 of said frame-member 2, and against which the arm or projecting portion 49 of said rotary valve-plate 38 is carried 90 when operated by said lever-arm 44 and moved to its shut off or closed position. By regulating the position of said stop-screw 53 the rotary valve-plate 38 may be stopped 95 to enlarge or decrease the opening or passage formed by the registered by-pass channels or grooves of the rotary valve-plate and stationary valve-plate, whereby more or less gas may be permitted to by-pass 100 or flow to the burner or torch of the blowpipe. A lock-nut 54 may be associated with said stop-screw 53 to secure the same in any desired adjusted position. Suitably secured to the free end of said lever-arm 44 is a hook-member 55, and when the 110 burner or torch of the blowpipe is not in use the same is hung upon said hook-member 55, whereupon its weight tends to move downward and hold down said lever-arm 44, whereby said rotary valve-plate 38 is moved 115 to and maintained in its closed or shut off position as above described.

The operation and advantages of the above described invention will be understood from the above description and inspection 120 of the accompanying drawings, without further explanation.

We claim:

1. In a device of the kind described, a stationary valve-plate provided with a pair 125 of noncommunication air ports and a pair of noncommunication gas ports, means for supporting said stationary valve-plate, air conveying means, gas conveying means, means for connecting said air conveying 130

- means in communication with said air ports and said gas conveying means in communication with said gas-ports, a movable valve-plate provided with a connecting air channel adapted to register with said air ports to pass air from one to the other and a connecting gas channel adapted to register with said gas ports to pass gas from one to the other, and means for moving said movable valve-plate to carry into and out of such registration said respective connecting channels, comprising a pivoted lever-arm, and means between said lever-arm and said rotary valve-plate whereby the oscillation of the former rotates the latter.
2. In a device of the kind described, a frame-member, a clamp-means for securing said frame-member to a work-bench or the like, a stationary valve-plate fixed upon said frame-member, said stationary valve-plate having a pair of non-communicating air passages and a pair of non-communicating gas passages, a rotary valve-plate registered against said stationary valve-plate, said rotary valve-plate having a connecting air channel and a connecting gas channel adapted to be moved into and out of communication respectively with said air passages and said gas passages of said stationary valve-plate by the rotation of said rotary valve-plate, a lever-arm pivoted to said frame-member, an extension connected with said lever-arm having an inwardly extending pin, a radially projecting portion connected with the rotary valve-plate having a slot to receive said pin, a stop on said frame-member adapted to limit the movement of said lever-arm to fix its normal position, a pull spring interconnecting said lever-arm with said frame-member to maintain the former in normal position, and a stop means limiting the rotary movement of said rotary valve-plate under the impulsion of said lever-arm.
3. In a device of the kind described, a stationary valve-plate provided with a pair of non-communicating air ports and a pair of non-communicating gas ports, said stationary valve-plate having a flat smooth face at which one end of each of said respective air and gas ports terminate, a journal projecting from said stationary valve-plate, a rotary valve-plate mounted on said journal, said rotary valve-plate having a flat smooth face registering slidably against the face of said stationary valve-plate, said rotary valve-plate being provided in its face with a connecting air channel and a connecting gas channel adapted to be moved respectively into and out of registration with said air ports and said gas ports of said stationary valve-plate by the rotation of said rotary valve-plate, and means for rotating said rotary valve-plate.
4. In a device of the kind described, a stationary valve-plate provided with a pair of non-communicating air ports and a pair of non-communicating gas ports, said stationary valve-plate having a flat smooth face at which one end of each of said respective air and gas ports terminate, a journal projecting from said stationary valve-plate, a rotary valve-plate mounted on said journal, said rotary valve-plate having a flat smooth face registering slidably against the face of said stationary valve-plate, said rotary valve-plate being provided in its face with a connecting air channel and a connecting gas channel adapted to be moved respectively into and out of registration with said air ports and said gas ports of said stationary valve-plate by the rotation of said rotary valve-plate, and means for rotating said rotary valve-plate.
5. In a device of the kind described, a stationary valve-plate provided with a pair of non-communicating air ports and a pair of non-communicating gas ports, said stationary valve-plate having a flat smooth face at which one end of each of said respective air and gas ports terminate, a journal projecting from said stationary valve-plate, a rotary valve-plate mounted on said journal, said rotary valve-plate having a flat smooth face registering slidably against the face of said stationary valve-plate, said rotary valve-plate being provided in its face with a connecting air channel and a connecting gas channel adapted to be moved respectively into and out of registration with said air ports and said gas ports of said stationary valve-plate by the rotation of said rotary valve-plate, and means for rotating said rotary valve-plate.
6. In a device of the kind described, a sta-

tionary valve-plate provided with a pair of non-communicating air ports and a pair of non-communicating gas ports, means for supporting said stationary valve-plate, air conveying means, gas conveying means, means for connecting said air conveying means in communication with said air ports and said gas conveying means in communication with said gas-ports, a rotary valve-plate provided with a connecting air channel adapted to register with said air ports to pass air from one to the other and a connecting gas channel adapted to register with said gas ports to pass gas from one to the other, said stationary valve-plate having a by-pass channel extending circumferentially from one of said gas ports, and said rotary valve plate having a by-pass channel extending circumferentially from one end of said connecting gas channel and adapted to register with said by-pass channel of said stationary valve-plate when said rotary valve-plate is moved to shut-off position to allow a minimum area of communication between said gas-ports of said stationary valve-plate, and means for rotating said rotary valve-plate.

7. In a device of the kind described, a stationary valve-plate provided with a pair of non-communicating air ports and a pair of non-communicating gas ports, means for supporting said stationary valve-plate, air conveying means, gas conveying means, means for connecting said air conveying means in communication with said air ports and said gas conveying means in communication with said gas-ports, a rotary valve-plate provided with a connecting air channel adapted to register with said air ports to pass air from one to the other and a connecting gas channel adapted to register with said gas ports to pass gas from one to the other, said stationary valve-plate having a by-pass channel extending circumferentially from one of said gas ports, and said rotary valve plate having a by-pass channel extending circumferentially from one end of said connecting gas channel and adapted to register with said by-pass channel of said stationary valve-plate when said rotary valve-plate is moved to shut-off position to allow a minimum area of communication between said gas-ports of said stationary valve-plate, and means for rotating said rotary valve-plate, comprising a pivoted lever-arm, and means between said lever-arm and said rotary valve-plate whereby the oscillation of the former rotates the latter.

8. In a device of the kind described, a frame-member, a clamp-means for securing said frame-member to a work-bench or the like, a stationary valve-plate fixed upon said frame-member, said stationary valve-plate having a pair of non-communicating air passages and a pair of non-communicating

gas passages, a rotary valve-plate registered against said stationary valve-plate, said rotary valve-plate having a connecting air channel and a connecting gas channel adapted to be moved into and out of communication respectively with said air passages and said gas passages of said stationary valve-plate by the rotation of said rotary valve-plate, said stationary valve-plate having a by-pass channel extending circumferentially from one of said gas ports, and said rotary valve plate having a by-pass channel extending circumferentially from one end of said connecting gas channel and adapted to register with said by-pass channel of said stationary valve-plate when said rotary valve-plate is moved to shut-off position to allow a minimum area of communication between said gas-ports of said stationary valve-plate, and means for rotating said rotary valve-plate, comprising a lever-arm pivoted to said frame-member, an extension connected with said lever-arm having an inwardly extending pin, a radially projecting portion connected with the rotary valve-plate having a slot to receive said pin, a stop on said frame-member adapted to limit the movement of said lever-arm to fix its normal position, a pull-spring interconnecting said lever-arm with said frame-member to maintain the former in normal position, and a stop means limiting the rotary movement of said rotary valve-plate under the impulsion of said lever-arm.

9. In a device of the kind described, a frame-member, a clamp-means for securing said frame-member to a work-bench, a stationary valve-plate fixed upon said frame-member, said stationary valve-plate having a pair of non-communicating air ports and a pair of non-communicating gas ports, said ports terminating at one end in a flat smooth surface provided at one side of said stationary valve-plate, socket portions in which the opposite ends of said ports terminate, air conveying means connected with the socket portions of said air ports, gas conveying means connected with the socket portions of said gas ports, a rotary valve-plate, a journal projecting from the smooth face of said stationary valve-plate upon which said rotary valve-plate is mounted, said rotary valve-plate having a flat smooth face registering slidably against the smooth face of said stationary valve-plate, said rotary valve-plate being provided in its face with a connecting air channel and a connecting gas channel the same being adapted to register respectively with said air-ports and gas-ports of said stationary valve-plate when said rotary valve-plate is moved to turned on position, and to move out of registration therewith when said rotary valve-plate is moved to turned off position, said stationary valve-plate having a by-pass

- channel extending from one of said gas-ports, and said rotary valve-plate having a by-pass channel extending from one end of said connecting gas channel and adapted to 5 register with said by-pass channel of said stationary valve-plate when said rotary-valve plate is moved to turned off position, an adjustable stop-member adapted to regulate the turned-off position of said rotary valve-plate to regulate the turned-off position of said rotary 10 valve-plate to increase or decrease the passage formed by said registered by-pass channels, a lever-arm pivoted to said frame-member, an extension connected with said lever-arm having an inwardly extending 15 pin, and means connected with said rotary valve-plate adapted to receive the engagement of said pin whereby oscillation of said lever-arm rotates said rotary valve-plate.
10. In a device of the kind described, a 20 frame-member, a clamp-means for securing said frame member to a work-bench, a stationary valve-plate fixed upon said frame-member, said stationary valve-plate having a pair of non-communicating air ports and 25 a pair of non-communicating gas ports, said ports terminating at one end in a flat smooth surface provided at one side of said stationary valve-plate, socket portions in which the opposite ends of said ports terminate, air 30 conveying means connected with the socket portions of said air ports, gas conveying means connected with the socket portions of said gas ports, a rotary valve-plate, a journal projecting from the smooth face of said 35 stationary valve-plate upon which said rotary valve-plate is mounted, said rotary valve-plate having a flat smooth face registering slidably against the smooth face of said stationary valve-plate, said rotary 40 valve-plate being provided in its face with a connecting air channel and a connecting gas channel the same being adapted to register respectively with said airports and gas-ports of said stationary valve-plate when 45 said rotary valve-plate is moved to turned on position, and to move out of registration therewith when said rotary valve-plate is moved to turned off position, said stationary valve-plate having a by-pass channel extending from one of said gas-ports, and 50
- said rotary valve-plate having a by-pass channel extending from one end of said connecting gas channel and adapted to register with said by-pass channel of said stationary valve-plate when said rotary-valve plate is moved to turned off position, an adjustable stop-member adapted to regulate the turned-off position of said rotary valve-plate to increase or decrease the passage formed by said registered by-pass channels, a lever-arm pivoted to said frame-member, an extension connected with said lever-arm having an inwardly extending pin, means connected with said rotary valve-plate adapted to receive the engagement of said pin whereby oscillation of said lever-arm rotates said rotary valve-plate, and a hook-member on the free end of said lever-arm upon which a blow-pipe burner or the like can be hung to hold said lever-arm in downwardly oscillated position to maintain said rotary valve-plate in its turned off position. 65
11. In a device of the kind described, a stationary valve-plate having an intake gas port and an outlet gas port in non-communicating relation to each other, and being further provided with an intake air port and an outlet air port in non-communicating relation to each other, gas conveying means, means for connecting the same in communication with said gas ports, air conveying means, means for connecting the same in communication with said air ports, and a rotary means associated with said stationary valve-plate for opening and closing 70 communication respectively between said gas ports and said air ports, a gas by-pass means operative to pass a small quantity of gas from one gas port to the other when said rotary means is in closing position, and 75 means for operating said rotary means. 80
- In testimony that we claim the invention set forth above we have hereunto set our hands this 20th day of June 1914.
